UNITED STATES PATENT OFFICE.

AUGUST BOHMAN, OF CHICAGO, ILLINOIS, ASSIGNOR OF ONE-HALF TO
CHARLES J. STROMBERG, OF SAME PLACE.

FOLDING STEP-LADDER.

SPECIFICATION forming part of Letters Patent No. 295,518, dated March 25, 1884.

Application filed December 13, 1883. (No model.)

To all whom it may concern:

Be it known that I, AUGUST BOHMAN, residing at Chicago, in the county of Cook and State of Illinois, have invented certain new and useful Improvements in Folding Step-Ladders, of which the following, in connection with the accompanying drawings, is a specification.

In the drawings, Figure 1 is a front view of the folded ladder. Fig. 2 is a like representation of the same unfolded. Fig. 3 is a side view of the ladder unfolded and set for use. Fig. 4 is a detail showing the construction of the ends of the steps. Fig. 5 is a section in the plane of the line $x-x$ of Fig. 2, viewed in the direction indicated by the arrow there shown. Fig. 6 is a detail of the detachable brace-bar. Fig. 7 is a rear view of a part of the means employed for connecting the brace-legs to the side rails. Fig. 8 is a detail showing the means attached to the brace-legs for coupling them to the side rails; and Fig. 9 is a sectional detail in the plane of the line $y-y$ of Fig. 7, viewed in the direction indicated by the arrow there shown.

Like letters of reference indicate like parts. A A represent the side rails of the ladder. Those sides of the rails A A which are toward each other are cut away bevelingly, as shown at $a-a$. In the shoulders $a'-a'$, at the junction of the beveled portions $a-a$, are small recesses $a''-a''$.

B B are the steps. These steps have tenons $b-b$ on their ends, which are pierced or have holes $b'-b'$ therein, to connect the side rails and steps together by arranging the tenons $b-b$ in the recesses $a''-a''$, and by passing pins $c-c$ through the shoulders $a'-a'$ and through the said tenons, thus linking or hinging the steps and side rails to each other in such a manner that the rails may be folded together, the steps then lying between the beveled parts $a-a$, as indicated in Fig. 1. In practice I deem it best to make the lower end of one rail and the upper end of the other somewhat thicker or broader than the remaining portions, as shown at $d-d$, and to cover the back and front side of both rails with strips or cleats $e-e$; but these features of construction are employed more for the purpose of giving the folded ladder a solid and symmetrical appearance than for

utility, although the folded ladder is thereby retained more firmly in its folded position, and the rails A A are prevented from rocking or tilting while folded, thus relieving the joints 55 of any strain at that time.

C C are the brace-legs.

D D are hinged plates, the lower parts of which have sockets in them to receive the upper ends of the legs C C, and on the upper parts of which plates are the headed studs or buttons D' D', rigidly attached thereto. I connect the legs C C to the lower parts of the plates D D, if need be, by means of nails, screws, or suitable similar fastenings. 65

E is a brace-bar, in the ends of which are eyes F F, and F' F' are hooks in the legs C C, arranged to enter the eyes F F.

G G are eyes on one face of the bar E, for the purpose hereinafter referred to. 70

H is a plate on the upper end or portion of each rail A, respectively. These plates stand out between their lateral edges from the rails A A, forming between the rails and plates recesses f f; and g is an opening adapted to receive the head of the stud or button D'. This opening has a contracted or narrow portion, as shown in Fig. 7, to receive only the neck of the stud D'. 75

I is a chain or cord connecting the rails A A and legs C C detachably.

In practice I deem it best to provide the ends of the steps B B with metallic caps.

This ladder may be used either with or without the legs C C; but as its convenience is 85 greatly increased by adapting it to be employed in connection with such legs, as occasion may require, I have provided means for attaching and detaching the legs with facility. To attach the legs C C to the rails A A, I arrange 90 the buttons D' D' in the openings g g and raise the legs until the heads of the buttons pass underneath the plates H H. To connect or brace the legs C C, I arrange the bar E so that the hooks F' F' will enter the eyes F F. 95 When not using the legs C C, I brace the rails A A by arranging the bar E, so that the eyes G G will engage hooks on the said rails.

Having thus described my invention, what I claim as new, and desire to secure by Letters 100 Patent, is—

1. A portable folding step-ladder in which

are combined the side rails, A A, having on their sides or faces the beveled portions a a, and the recesses a" a", and the steps B B, having on their ends tenons b b, entering the said recesses, and there hinged or jointed to the side rails, substantially as and for the purposes set forth.

2. A portable folding ladder, combined with the brace-legs C C, and means for connecting to the said legs detachably to the side rails, and

the detachable brace-bar E, substantially as and for the purposes set forth.

In testimony that I claim the foregoing as my own I hereto affix my signature in presence of two witnesses.

AUGUST BOHMAN.
